UNITED STATES PATENT OFFICE.

ESECK C. MILLER, OF NEWARK, NEW JERSEY, ASSIGNEE TO IMPERIAL STOPPER COMPANY, A CORPORATION OF MAINE.

BOTTLE-FEEDING MACHINE.

1,106,884.

Specification of Letters Patent. Patented Aug. 11, 1914.

Application filed November 21, 1911. Serial No. 631,455.

To all whom it may concern:

Be it known that I, ESECK C. MILLER, a citizen of the United States, residing at Newark, in the county of Essex and State of New Jersey, have invented certain new and useful Improvements in Bottle-Feeding Machines, of which the following is a full, clear, and exact description.

This invention relates to bottle feeding appliances and more particularly to a novel capping machine, and has for one of its objects the provision of means for expeditiously transferring bottles, or the like, from some convenient point over to a principal operating part, which in a preferred form of device is a capping head, together with co-acting mechanism for removing said bottles from said transferring means; the handling of the bottles being rapid and being further more accomplished substantially without possibility of breakage.

In the preferred form of my invention herein exemplified, the transferring elements are rotarily mounted as far as practicable; which renders the mechanism very efficient in action.

These and other objects of my invention will be hereinafter referred to and the novel elements and combinations of elements whereby said objects may be attained will be set forth in the appended claims. I am aware, however, that many modifications and changes may be made within the spirit of my invention and I hence desire to be limited only by the scope of the said claims.

In the accompanying drawings which form a part hereof and in which like reference characters designate like parts throughout the several views, I have exemplified a preferred form of my invention.

Referring to said drawings: Figure 1 is a horizontal section through a capping machine, taken on line I—I of Fig. 2. Fig. 2 is a side elevation of said machine with portions thereof broken away for purposes of illustration. Fig. 3 is a section taken on line III—III of Fig. 2. Fig. 4 is a detail section of the yokes, yoke plate and adjoining parts. Fig. 5 is a fragmentary detail of the main table. Fig. 6 is a detail section taken on line VI—VI of Fig. 1, the section being viewed in the direction of the arrow.

Referring first to Figs. 1 and 2, the mechanism therein illustrated comprises a base 1 from which extends upwardly a standard 2. Within this standard is a reciprocable shaft 3 which is connected by means of a link 4 and wrist pin 5 to a crank disk 6, upon a driving shaft 7, which is driven by means of a pulley 8. Reciprocation of shaft 3 correspondingly raises and lowers the capping head 9, which latter may be provided with the usual hopper 10 containing caps which are fed to the capping throat in a well known manner. Upwardly projecting from the base 1 in front of the capping head 9 is a stationary upright 11 which may be secured to the base by means of bolts 12, or the like, and within which is a shaft 13, the lower extremity of which carries a wheel 14, which forms part of a step by step gear. The contour of this wheel is best shown in Fig. 3, wherein it will be observed that a series of radial slots 15 extend inwardly from the periphery of the wheel toward the shaft 13, said slots being disposed around said periphery at spaced intervals. Between slots 15 are arcuate depressions 16, the purpose of which will be hereinafter noted. To one side of shaft 3, as viewed in Fig. 3, is a spindle 17 which is disposed in parallelism with the shaft 13 and carries upon the upper extremity thereof a crank arm 18 provided with a roller 19, which roller is adapted to enter and neatly engage the walls of slots 15. Crank 18 has a lip 20 upstanding from the edge of the circular hub thereof, and a line drawn through the axis of the shaft or spindle 17 and through the axis of the roller 19 will intersect this lip substantially in the middle of the length thereof. It is obvious that rotation of the spindle 17 will effect a step by step advancement of wheel 16, since roller 19 will engage a slot 15 and will thereby drive wheel 14 around a determined distance and will emerge from said slot preparatory to reengaging the next slot to the rear. As the roller is emerging from a slot, however, the lip 20 comes into engagement with the arcuate depression or recess 16 immediately adjacent and behind the said slot, and this engagement serves to lock wheel 14 against rotation until the other extremity of the ridge passes out of engagement with

said recess, at which instant roller 19 has again entered a slot 15. Spindle 17 may be driven in any suitable manner, as by means of miter gears 21 shown in Fig. 2, one of these gears being mounted upon said spindle, and the other being secured to the threaded extremity of a counter-shaft 22, which extends parallel to the shaft 7, above referred to.

For convenience of illustration shaft 22 has been broken away partly in Fig. 2. The rear extremity of this shaft carries a gear 23 which is in mesh with the gear 24 mounted upon shaft 7; and as these two gears are preferably of the same diameter, it is evident that for every revolution of the shaft 7 the shaft 13 will advance one step. In this instance the shaft 7 must make eight revolutions in order to effect a complete revolution of shaft 13. Mounted upon the upper extremity of the shaft 13 is a yoke plate or disk 25, best shown in Figs. 1 and 4. I prefer to reduce the upper extremity of shaft 13 and to place thereon a collar 26 which is seated against the shoulder formed by the reduction in the diameter of the shaft, and the plate or disk 25 is pressed firmly into engagement with this collar 26 by means of a nut 27, mounted upon the threaded end 28 of shaft 13. In order to prevent inadvertent displacement of the disk 25 with respect to collar 26 a dowel 29 may be provided, and the collar 26 from which the dowel projects preferably has a forced fit with the shaft 13. The yokes 30 carried by yoke plate 25 will hence invariably be disposed in proper relationship to the capping head when the latter is caused to descend. There are eight of these yokes in the present instance, shaped substantially as shown in Figs. 1 and 4. It is obvious, of course, that these elements may be of any suitable configuration adapted to receive and convey bottles, or the like, over the surface of the table 31, but I prefer to form them in the shape of double yokes, the respective upper and lower portions of which are substantially U-shaped, and the arms of the U's each having offset portions 32. The said portions 32 of adjoining yokes project toward each other and serve to prevent the inadvertent admission of a bottle into any other part of the rotary structure than the bottle receiving pockets provided by the yokes. Each of these yokes is provided with a radially directed and bifurcated lug 33, which is adapted for engagement with the plate 25 and is secured thereto in any suitable manner, as by means of bolts 34. The assembled yokes therefore form a substantially circular frame in which are a series of recesses or pockets adapted for the reception of the bottles to be capped. The table 31 is normally stationary, but is adapted to be raised or lowered upon the upright 11,

by means of a screw 35. To this end the hub 36 of the table which receives the upright is provided with a lug 37 adapted for the reception of said screw 35; and a bracket 38 is secured below and in alignment with said lug, to the side of the standard 11. Screw 35 is threaded through this bracket and may be locked against inadvertent displacement therein by means of a set screw 39. When the screw has been set the table 31 may be raised or lowered by applying a span-wrench to the nut 40, which is in engagement with lug 37. In order to prevent the table from swiveling around, the side of the standard may have a spline 41 cut therein adapted for the reception of the end of a bolt 42 threaded into the hub of the table.

The table 31 is preferably provided with an upstanding flange 43 which extends therearound and in fact projects therebeyond through a somewhat over ninety degree angle; and while the contour of the table is generally circular, there is a laterally projecting portion 44, which also is provided with an upstanding flange upon either side thereof, the said flanges being respectively designated 45 and 46. The inner end of a flange 46 is arcuate in conformity with flange 43, and the table is recessed between the opposed extremities of flanges 43 and 46, as at 47; recess 47 being preferably directly in front of the standard 2. The small table 48 of a suitable compensating mechanism 49 normally substantially fills recess 47, but may be driven downwardly in a well known manner when the mechanism is in operation. The particular construction of the compensating mechanism will not be herein further considered since mechanisms of this character are well known and since said mechanism *per se* forms no part of the present invention. Adjustably mounted upon the upright 11 is a bracket 50, the arm of which extends laterally away from said upright, and the said arm is provided at its outer extremity with a bearing 51 in which is mounted a shaft 52. The lower extremity of this shaft carries a yoke-shaped member 53, to which is connected a cylinder 54; the cylinder 54 being attached in this instance to the member 53 by means of a universal joint connection 55. Within the cylinder 54 is a short rod 56 which preferably is splined to said cylinder, the key-way being shown at 57. The lower extremity of rod 56 is connected to a yoke-shaped member 58 similar to that designated 53 by the universal joint connection 59. Member 58 is mounted upon the upper extremity of a short shaft 60 which is journaled in a suitable gear casing 61 secured to the base 1. This casing serves to inclose a chain of gears, one gear 62 being secured to the lower extremity of shaft 60, and being

in mesh with a pinion 63, which in turn is in engagement with a similar pinion 64, the latter being driven by a third pinion 65. The ratio of speed reduction between shafts 17 and 60, it may here be noted, is in this 5 instance two to one.

Upon the upper extremity of the shaft 52 is a plate 66, the hub of which bears against the upper face of the bearing 51, and is supported thereby. It is obvious that as the gear 17 is rotated eight times to advance the yoke plate through one revolution, disk 66 will be rotated four times. An auxiliary bracket 67 is secured to one side of the bearing 51, and this bracket in turn carries a small feed table 68, the upper surface of which is in a plane with the upper surface of the disk 66. Immediately above the member 53 on the shaft 52 is a cam 69, the contour of which is best shown in dotted lines in Fig. 1. The link 70 is slotted at one extremity 71 thereof for the reception of shaft 52; link 70 being guided thereby; and the said link carries a roller 72 adapted for 10 engagement with the cam 69. The outer extremity of link 70 is connected to a crank 73 mounted upon the lower extremity of a shaft 74, which is journaled in the table 68 and projects therethrough; and the upper extremity of this shaft carries a finger 75, the outer end of which is up-turned as at 76 for engagement with the rear arm 77 of a latch, broadly designated 78. This latch is pivotally mounted at 79 upon plate 68. The 15 plate 68 is provided with a flange 80 which serves as a guide for the bottles; a portion of this flange extending around a part of the arcuate recess in the plate 68 which receives the disk 66. This curved section of 20 said flange is slotted, as at 81, for the reception of the bottle engaging portion 82 of the latch 78, and the end 83 of this slot 81 serves as a stop for the latch in the direction in which it is normally urged by the spring 25 84. The outer extremity of the rib 80 is preferably enlarged for the reception of a pin 85, upon which is mounted a yielding guide 86, which projects outwardly from the edge of the table 68 over the edge of the bottle filling table 87. The filling table is in 30 this instance circular and adapted for rotation in the direction of the arrow disposed thereon. Around the periphery of this table are a series of somewhat peculiarly shaped 35 ribs or projections 88, the interior half or two-thirds of said projections being adapted to substantially conform to the surface of a bottle 89, which may be placed thereagainst, while the outer extremity of each of said 40 45 50 55 60 65 70 75 80 85 90 95 100 105 110 115 120 125 130 135 140 145 150 155 160 165 170 one side of member 107 is a finger 109, pivotally mounted as at 110 upon the main table, this finger being normally held in engagement with the base of the member 107 by means of a spring 111.

To one side of finger 109 is mounted a star wheel 112, the said wheel being rotated by means of a shaft 113, which is journaled in the main table, and the lower extremity 19 of which shaft carries a bevel wheel 114. This wheel is in mesh with a bevel pinion 115, the ratio of teeth in the said wheels 114 and 115 being preferably one to two. Pinion 115 is mounted upon the extremity 15 of a shaft 116, which is journaled in a bracket 117, the said bracket being secured upon the under side of the main table. The other extremity of shaft 116 carries a sprocket wheel 118, around which passes a 20 chain 119, said chain being driven from a sprocket pinion 120 mounted on shaft 22. The table 31 is preferably apertured as at 121.

The operation of the mechanism will now 25 be described. Assuming that the filler table 87 is being driven at a uniform rate in the direction of the arrow thereupon and that the pulley 8 is driven in the direction of the arrow indicated thereon; the head 9 will be 30 reciprocated through the instrumentality of shaft 7, disk 6, link 4, and reciprocating shaft 3, once for every revolution of the pulley 8. The shaft 22 will be rotated in the direction opposite shaft 7, but in synchronism therewith, since the gears 23, 24, have a one to one ratio, and this shaft in turn will drive the spindle 17 clockwise, as viewed from above. This rotates the crank 18 in the direction of the arrow adjacent thereto, causing 35 the roller 19 thereof to successively engage the slots 15 of the wheel 14. The step by step motion thus imparted to wheel 14 is transmitted to the bottle frame, which comprises the yokes 30 and their supporting 40 plate and rotates this structure through forty-five degrees, counter-clockwise, as viewed from above, for every revolution of the pulley 8. Simultaneously the shaft 60 is rotated at half the speed of shaft 17 by reason 45 of the train of gears therebetween, so that disk 66 is rotated once during every two revolutions of the pulley. The bottles 89 which have been disposed within the curved projections 88 are carried around by the 50 filler table until they engage the yielding guide 86. The spring 86' which normally controls this guide is sufficiently strong to prevent the latter from swinging away from its determined position, except in an emergency 55 where the progress of the bottles through the machine has become stopped, in which event it is obvious, of course, that if guide 86 did not yield, damage, and probably breakage of the bottles, would ensue.

60 As guide 86 is angularly disposed for the

most part it wipes the bottles delivered thereagainst successively in toward passage 91. It cannot, however, drive them completely onto the table 68; but the projection or rib 88 next following does so drive the 70 bottle which has been displaced from the pocket in advance, completely onto the table 68 by means of the preferably straight portion of the said rib or projection. Succeeding bottles will crowd those thus previously 75 driven onto the said table through passage 91 onto the rotating disk 66, and as the latter is continuously driven such bottles will be immediately advanced against the crooked end of the arm 82 of latch 78. As this latch is normally held by its spring in the position in which it is shown in Fig. 1, further advance of the bottles is impeded thereby. Twice in every revolution, however, of the plate 66 a nose of the cam 69 urges roller 72 80 to its outermost position, and this action causes link 70 to correspondingly displace crank arms 73 and 75, and to thereby swing latch 78 at stated intervals. Thus the latch 85 90 will be swung, if cam 69 be properly disposed, just before a bottle receiving pocket in the rotary frame has been moved into adjacency to said latch. The swinging of the latch therefore permits a bottle, after one has been disposed in adjacency thereto, to be 95 driven around by the plate 66 until the said bottle has been moved into the pocket provided therefor in the frame. Immediately thereafter latch 78 snaps to and impedes progress of succeeding bottles until the next 100 105 bottle receiving pocket approaches it. If a bottle has not been rotated by plate 66 quite into contact with arm 82 before the latch starts to open, and thereby happens to be pinched more or less between the elbow of the arm 82 and the adjacent end of the guide 90, no harm will result, since the bottle will either be swept into its pocket by the closing action of the latch, or it will be driven back upon plate 66, to be there held 110 to await the approach of the next pocket. Only one other contingency need be considered, and that is when the bottle has become so positioned with respect to the elbow 115 of the latch and the adjacent extremity of the guide 90 that the closure of the latch merely clamps the bottle therebetween. Here again, however, no harmful action can occur, since the approaching nose of the frame at the outside of the bottle receiving 120 pocket will merely drive such a bottle back so that the latch may thereupon further close and hold it back upon plate 66. Bottles so held, it will be understood, are slid over the surface of the rotating disk until free to 125 advance therewith by the opening of the latch in the manner described. The plate 68 is adjusted with respect to the filler table so that the bottles may be wiped off into passage 91 as described, by raising or lowering 130

the bracket 50; while the table 31 is elevated or lowered independently of table 68, by means of the screw 35. No matter whether the table 31 be somewhat above or 5 somewhat below the level of table 68, bottles may be advanced thereupon from disk 66 by reason of the fingers 96, whose action has previously been considered. Bottles forced by the action of disk 66 and latch 78 into 10 the pockets in the rotary frame are carried around by a step by step motion until they are successively disposed upon the table 48 of the compensating mechanism, at which point they are capped in the usual manner 15 by means of the capping head 9; the bottles, of course, being stationary while the capping head is applying caps thereto.

Bottles traversing the fingers 96 and table 31 are held within the pockets in the carrying frame by means of the flanges 43. If, 20 however, such bottles have not been driven, by the action of plate 66, as far into the bottle receiving pockets as they should be in order to have the cap applied properly 25 thereto, or are misplaced from any other cause, such bottles are wiped back radially into said pockets by the wiping finger or lever 104. Spring 105 is only sufficiently strong to just effect such displacement of 30 the bottles. As the bottles, however, are delivered upon the same table 48 the clamping finger or lever 101 presses them firmly into their pockets and thereby centers them with respect to the capping head. The wiping 35 lever 104 is provided merely to force the bottles well back into the pockets before they encounter the clamping lever. It is, of course, obvious, that under certain conditions the wiping lever may be eliminated. 40 Bottles leaving the compensating table 48 are carried around into engagement with the nose 108 of the member 107, which wipes them radially out from the pockets in which they have been carried and drives them successively into engagement with the finger 45 109. This finger serves to steady their motion and prevents them from upsetting. Pressure of the bottles against finger 109 causes the latter to swing clockwise, as 50 viewed in Fig. 1, about its pivotal axis until the bottle which presses against the said finger has been received into one of the depressions in the periphery of the star wheel 112. This wheel is driven at such a rate 55 that one of the pockets therein will invariably be ready to receive a bottle ejected from a pocket in the yoke frame. The bottles so disposed between the prongs of the star wheel are swept around thereby until 60 they encounter the wiping member 122, which forces them out of engagement with the said wheel so that they merely accumulate upon the extension 44 of the table 31. The star wheel 112, it may be noted, is preferably formed in two parts as shown in Fig. 65

6, the star shaped bodies of said parts being spaced from each other by means of their hubs, and the member 122 projects into the space between said bodies, as shown. The latch-cam drive preferably comprises the 70 telescoping cylinder 54 and rod 56, constructed in the manner described, since thereby the table 68 may be raised, or lowered in order to make it correspond with the filling table, without affecting said drive. 75

Having described my invention, I claim:

1. The mechanism for handling bottles which comprises a rotary structure having pockets adapted for the reception of bottles, means for rotating said structure, a normally stationary member below said structure and constituting a floor over which the bottles in said pockets are moved, means for delivering bottles to said pockets, and means for adjusting said member vertically with respect to said means. 30

2. The mechanism for handling bottles which comprises a rotary structure having pockets adapted for the reception of bottles, means for rotating said structure, a normally stationary member below said structure and constituting a floor over which the bottles in said pockets are moved, means for delivering bottles to said pockets, means for adjusting said member vertically with respect to said bottle delivering means, and means for supporting said bottles when moving onto said member from said delivering means. 35

3. The mechanism for handling bottles which comprises a rotary structure having pockets adapted for the reception of bottles, means for rotating said structure, a normally stationary member below said structure and constituting a floor over which the bottles in said pockets are moved, means for delivering bottles to said pockets, means for adjusting said member vertically with respect to said bottle delivering means, and a plurality of elements movable with respect to each other for supporting said bottles when moving onto said member from said delivering means. 100

4. The mechanism for handling bottles which comprises a rotary structure having pockets adapted for the reception of bottles, means for rotating said structure, a normally stationary member below said structure and constituting a floor over which the bottles in said pockets are moved, means for delivering bottles to said pockets, means for adjusting said member vertically with respect to said bottle delivering means, and a plurality of pivoted fingers movable with respect to each other for supporting said bottles when moving onto said member from said delivering means. 105

5. In a bottle capping machine, a horizontal rotary bottle carrier in combination with a table beneath the same and over which the 110

bottles slide when moved by the carrier, said table being vertically adjustable and a section thereof which is traversed by the bottles, being adjustable to different inclinations for the purpose set forth.

6. In a bottle capping machine, a horizontal rotary bottle carrier in combination with a table beneath the same and over which the bottles slide when moved by the carrier, said table being vertically adjustable and a section

thereof which is traversed by the bottles, being adjustable to different inclinations, said section being composed of a plurality of arcuate strips, as set forth.

In witness whereof, I subscribe my signature, in the presence of two witnesses.

ESECK C. MILLER.
